TUCKING MECHANISM FOR WRAPPING MACHINES

Valentine Pearce Harvey, London, England, assignor to Molins Machine Company Limited, London, England, a British company

Application August 21, 1947, Serial No. 769,801
In Great Britain August 26, 1946

4. Claims. (Cl. 53—151)

1

This invention concerns improvements in or relating to wrapping or packing machines and refers more particularly to machines of the kind in which the articles to be wrapped or packed are moved by pushers on a continuous conveyor through wrapping mechanism. On such machines a wrapper is often folded about an article in such manner that parts thereof extend beyond the face of the article which is engaged by the pusher and usually, when the article is of rectangular block shape, the wrapper extends equally from all four edges of the end face. These extensions are folded down on to said face by folding opposite pairs in succession. For articles of thin rectangular block shape such as cigarette packets there are two broad extensions and two narrow ones and it is usual to describe the folding of the narrow ones as "tucking" and this term will be used hereafter for convenience.

It will be appreciated that the folding operations cannot be effected or at least completed unless the partly wrapped article is moved in advance of the pusher piece and this may be done by rollers as in United States patent specification No. 1,517,307 or by movable linkwork as in British patent specification No. 252,216 and the present invention has for an object the provision of an improved device of the latter class.

According to the invention there is provided tucking mechanism for machines of the kind referred to comprising a pivoted tucker movable laterally of the article path to effect the tucking operation and lengthwise of the path to remove the article from the pusher of the conveyor and means for operating the tucker so that its operative face lies at a comparatively large angle (e. g. 45°) to the end face of the article at its first engagement with the wrapper and thereafter swings during its movement lengthwise of the path until it is substantially parallel with said end face. The tucker may be so arranged that at first contact with the wrapper it engages with its extremity a portion of the wrapper which extends beyond the article near to (e. g. at a distance not more than about one third of the thickness of the article from the end face of the article) and at the end of the movement it is lying in contact with the extension which is itself in contact with the end face. Thus the tucker practically pivots on the corner of the article and in this way the tuck is executed with extreme precision and neatness and the resulting fold is smooth and taut. The tucker may be operated by a crank and connecting rod to execute the lengthwise movement while the lateral move-

2

ment may be made by a cam. Two cams and followers may be employed to avoid the use of a spring and secure positive and accurate motion of the tucker. A spring may be interposed between the tucker and the cam mechanism as a safeguard to prevent damage through accident though normally the spring is not brought into play.

10 The invention will be more particularly described with reference to the accompanying drawing in which:

Figure 1 is a plan of part of a wrapping machine showing the mechanism for tucking one side of the wrapper;

15 Figure 2 is an end elevation of Figure 1.

Referring to the drawing, the article 1 which is in this case a cigarette carton and partly enclosed in a transparent wrapper 2 is moved along a path between side guides 3 by a pusher piece 4. The latter is attached to a continuous conveyor in the well-known manner but this is omitted from the drawing for simplicity. In practice the conveyor is usually an endless conveyor consisting of chains running over sprocket wheels at each end of the machine.

20 A tucker 5 is fixed at the free end of a lever 6 which is pivoted at 7 to a lever 8 which is pivoted at 9 to a cam lever 10. The cam lever is provided with two followers or rollers 11 which engage cams 12 and 13 which are rotatable about an axis 14. Thus the movements of the cam lever about its pivot 9 are positive in both directions. The cam lever is operatively coupled to the lever 8 through a stiff spring 15 which can give should the tucker come into engagement by accident with a pusher, for example in setting the machine or if the article jams by accident. A lug 20 on the lever 10 locates the lever 8 in position against the action of the spring 15. A connecting rod 16 is pivoted at 17 to the lever 6 and its other end is mounted on a crank pin 18 fixed on the cam 12. As the mechanism moves, the tucker describes a path substantially as shown by the chain line and effects the tucking operation and thus the tucker follows the wrapper extension as the latter bends about the corner of the carton face.

25 The tucker is also shown in an intermediate position in chain lines and actually in contact with the wrapper at the corner of the carton but a certain amount of latitude is allowed for in the engagement by making the cams adjustable about the axis 14. It is thought that the best adjustment for the tucker is so to arrange it that at first contact with the wrapper it engages with its extremity a portion of the wrapper

which extends beyond the article near to (e. g. at a distance not more than about one third of the thickness of the article from the end face of the article) and at the end of the movement it is lying in contact with the extension which is itself in contact with the end face. However, the actual adjustment employed depends on the nature of the material, the general performance of the machine and the opinion of the user. In this intermediate position the tuckers have moved the article a short distance in advance of the pusher as they move faster, as indicated by a long arrow, than the pusher which moves at a slower rate indicated by the short arrow and this difference in speed is maintained until the pusher is quite clear of the wrapper whereafter the pusher can move round the conveyor sprocket wheel and beneath the bed of the machine without disturbing the lower broad fold of the wrapper which can then be folded down on to the article in any known manner.

The guides 3 may be slotted as shown in Figure 2, where they are shown partly in section on the line 2—2 of Figure 1, and the tuckers 5 are in that case forked so that the article is controlled by the guides while tucking is taking place. Alternatively a narrower tucker, not forked, may be employed in which case the guides have a single slot to accommodate the tucker.

For simplicity, only one tucker is shown in the drawing, but normally there will be another similar tucker to operate on the other rear corner of the packet. Both tuckers operate simultaneously and similarly.

It will be seen that by means of the present invention the tucker engages at an angle the face of the portion of the wrapper extending beyond the article, that is to say, it engages the wrapper somewhere between the end of the article and the end of the extending portion. Thereafter the tucker swings, during its movement lengthwise of the path of the article, about the corner of the end face of the article until it is substantially parallel with said end face. During this swinging movement the tucker has a bodily translation inwardly whereby the wrapping material being folded by the tucker tends to be drawn around the corner of the end face of the article, and in this way a neat end fold is provided.

What I claim as my invention and desire to secure by Letters Patent is:

1. In a wrapping machine having conveyor means to move articles along a straight path during wrapping, tucking mechanism comprising in combination a tucking element having a surface for engaging and folding a rearwardly ex-

tending part of a wrapper on an article being conveyed, a support on which said element is pivoted for oscillating movement, independently of movement of said support, in a plane containing said path from an initial article engaging position, in which said surface forms an acute angle with said path, to a position substantially perpendicular to said path, means for oscillating said element to cause said surface to move lengthwise of said path in the general direction of travel of the articles, and to alter continuously the angular relation of said surface to said path, and mechanism driven in timed relation to said means for so displacing said support toward and away from said path that said element moves toward said path during pivotal movement of said element with said articles and while said surface is in engagement with the article wrapper, whereby the part of the wrapper being folded tends to be drawn around the corner of the end face of the article.

2. Mechanism as claimed in claim 1, wherein the tucking element is so arranged and timed relatively to the conveyor means that the wrapper-engaging surface at its first contact with a wrapper engages with its extremity a portion of the wrapper which extends beyond the article near to the end face of the article, and at the end of the movement is lying in contact with the said extending portion which is itself in contact with the end face.

3. Mechanism as claimed in claim 1, wherein the means to cause pivotal movement of the tucking element comprises a crank and a connecting rod connecting said crank to said element, and wherein the mechanism for displacing said support comprises a cam and a cooperating cam follower carried by said support.

4. Mechanism as claimed in claim 3, comprising a spring interposed between and operatively connecting said tucking element and said cam lever to prevent damage.

VALENTINE PEARCE HARVEY.
